(57) **CLAIM**

The ornamental design for a vibration and temperature compound sensor, as shown and described.

DESCRIPTION

FIG. 1 is a front view of a vibration and temperature compound sensor;

FIG. 2 is a back view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

The broken lines depict portions of the vibration and temperature compound sensor that form no part of the claimed design.
